United States Patent Office

Des. 185,217
Patented May 19, 1959

185,217

WHEELBARROW

Harry A. Liljenberg, Cleveland, Ohio, assignor to Modern
Tool & Die Company, a corporation of Ohio

Application May 12, 1958, Serial No. 50,854

Term of patent 14 years

(Cl. D14—3)

Fig. 1

Fig. 2

Fig. 1 is a perspective view of a wheelbarrow with a fender showing my new design, the side opposite being substantially similar and the back being conventional;

Fig. 2 is an enlarged perspective view of the fender portion, the side not shown being similar.

I claim:

The ornamental design for a wheelbarrow, as shown and described.
